SHUTTLE BOX FOR LOOMS

Filed Nov. 12, 1924

UNITED STATES PATENT OFFICE.

OSBORNE C. CASSELL, OF WINCHESTER, VIRGINIA, ASSIGNOR TO CROMPTON & KNOWLES LOOM WORKS, OF WORCESTER, MASSACHUSETTS, A CORPORATION OF MASSACHUSETTS.

SHUTTLE BOX FOR LOOMS.

Application filed November 12, 1924. Serial No. 749,529.

This invention relates to improvements in shuttle boxes for looms and an object of the invention is the provision of surfaces of revolution rotatable in one direction to reduce friction but held against rotation in the other direction to increase friction against the shuttle.

In very broad looms where the shuttle is required to move as much as forty feet in its flight it is desirable that considerable resistance be offered to the shuttle as it leaves the box at the beginning of the flight so that the pick may be strong and it is further desirable that the entry of the shuttle into the distant box shall be made as easy as possible to aid the shuttle to enter the box when its force is about spent. Under such conditions it is desirable that the surfaces of revolution should rotate as the shuttle enters the box.

It is to be understood that as shown in the drawings herewith the rolls will prevent rebounding of the shuttle, this feature making its use on relatively narrow looms desirable as well as on the broader looms.

Another object of my invention is to provide a plurality of surfaces of revolution rotatable in one direction only associated with a rolling surface mounted on the protection finger.

With these and other objects in view which will appear as the description proceeds, my invention resides in the combination and arrangement of parts hereinafter described and set forth in the claims.

In the drawings, Fig. 1 is a top plan view of a shuttle box having my invention applied thereto.

Fig. 2 is a front elevation of a lay showing the shuttle box, protector finger and the rolls, one of which is indicated in section, and

Fig. 3 is an enlarged detailed fragmentary front elevation of the lower end of one of the rolls showing the means for preventing retrograde movement.

Referring to the drawings it will be seen that I have provided a lay 10 provided with a box plate 11 and lay end 12 from which extends boss 13. A box back 14 of any desired construction may be employed and is provided with a flat friction surface 15 forming the rear wall of the box.

My invention relates more particularly

to the formation of the front part of the box and it will be seen that I have provided a plurality of studs 20 each having a head 21 and provided with loose collars 22 which extend between a shoulder 23 and the box plate. The studs have threaded shanks 24 extending through slots 25 in the box plate to receive nuts 26 by means of which the studs are held in fixed relation with respect to the box. Mounted loosely between the head 21 and the washer 22 of each of the studs 20 is a roll 27 having a surface of revolution indicated at 28 which may be made of any desired material, such as leather or fiber. The lower end of each roll is formed with ratchet teeth 29 as shown in Fig. 3, where it will be seen that a spring detent 30 is secured to the box plate by means of screw 31. There is a detent for each roll on the box plate. The teeth and detents as shown herein permit rotation of the rollers 27 in a clockwise direction as viewed in Fig. 1 but prevent rotation in a counter-clockwise direction. It is to be understood that I may furnish as many of the rolls as are necessary and that the latter are positioned for engagement with the front wall of the shuttle S, being opposite the surface 15 and cooperating therewith to exert lateral pressure against the shuttle in all angular positions of the roll.

Fixed to protector rod 32 which is received by boss 31 is a protector finger 33 the upper end of which is provided with a stud 34 and collar 35 similar to stud 20 and collar 22, respectively. The stud 34 supports a roller 36 which is freely rotatable in both directions and cooperates with the fixed rolls to exert pressure on the shuttle.

From the foregoing it will be seen that I have provided a shuttle box with a plurality of surfaces of revolution rotatable in one direction only and located so that said surfaces are equally distant from the box back in all angular positions. The position of the rolls may be varied with respect to the box back by reason of the slots 25. Furthermore it will be noted that the rolls rotate about fixed axes and are in contact with the widest portions of the shuttle to exert lateral pressure thereon.

Having thus described my invention it will be apparent that changes and modifica-

tions may be made therein by those skilled in the art without departing from the spirit and scope of the invention, and I do not wish to be limited to the details herein disclosed, but what I claim is:

5. In a loom, a shuttle box, rotary members forming one of the shuttle engaging sides of the box and positioned to engage the shuttle and have frictional contact therewith when the shuttle is in the box, and means including a pawl and ratchet to prevent movement of the rotary members in one direction. 35
10. In a loom, a shuttle box, a frictional surface forming part of the box to engage one part of the shuttle and fixed relatively to the box, and surfaces of revolution forming another part of the box and spaced from the fixed surfaces to engage other parts of the shuttle and be rotated thereby in one direction only as the shuttle moves in the box. 40
15. In a loom shuttle box, a plurality of shuttle-engaging rotary members to resist movement of a shuttle and forming one side of the box and rotatable in one direction only. 45
20. In a loom, a shuttle box, and means associated with the box to have rolling contact with the shuttle as the latter moves in one direction and having sliding frictional contact with the shuttle as the latter moves in the opposite direction. 50
25. In a loom, a shuttle box, a surface of revolution associated with the box to engage the shuttle as the latter enters the box, and means to permit said surface of revolution 55 to rotate in one direction only.
30. In a loom, a shuttle box, rotary members forming one of the shuttle engaging sides of the box and positioned to engage the shuttle and have frictional contact therewith when the shuttle is in the box, and means including a pawl and ratchet to prevent movement of the rotary members in one direction. 35
35. In a loom, a lay, a shuttle box, a frictional shuttle engaging surface fixed relatively to the shuttle box, means presenting surfaces of revolution to engage the shuttle and spaced from the first named surface, the surfaces of revolution being substantially the same distance from the fixed friction surface in all angular positions of said surfaces of revolution, and means to permit rotation of said surfaces of revolution in one direction only. 40
40. In a loom, a lay, a shuttle box thereon, a protector finger mounted on the lay, and a plurality of spaced surfaces of revolution forming one of the shuttle engaging sides of the box to resist movement of the shuttle in the box and have rolling contact therewith, one of said surfaces of revolution being mounted on the protector finger. 45
45. In testimony whereof I have hereunto affixed my signature.

OSBORNE C. CASSELL.
